United States Patent

Des. 237,701
Patented Nov. 18, 1975

237,701

BICYCLE

Roy R. Vachon, Rolling Hills, Calif., assignor to
W. R. Grace & Co., New York, N.Y.

Continuation-in-part of abandoned design application Ser.
No. 527,471, Nov. 26, 1974. This application Dec. 23,
1974, Ser. No. 535,766

Term of patent 14 years

Int. Cl. D12—11

U.S. Cl. D12—111

FIG. 6

FIG. 2

FIG. 1 is a top plan view of a bicycle showing my new design;

FIG. 2 is a side elevational view thereof;

FIG. 3 is a front elevational view thereof;

FIG. 4 is a rear elevational view thereof;

FIG. 5 is a side elevational view thereof opposite to that shown in FIG. 2; and

FIG. 6 is an enlarged, fragmentary plan view of the tread pattern which is repeated throughout the circumference of the front and rear tires of the bicycle.

This is a continuation-in-part of design application Ser. No. 527,471, filed Nov. 26, 1974, and now abandoned.

I claim:

The ornamental design for a bicycle, as shown and described.
